UNITED STATES PATENT OFFICE

ALBERT P. FALL, OF TOLEDO, OHIO, ASSIGNOR TO THE WEL-EVER PISTON RING COMPANY, OF TOLEDO, OHIO, A CORPORATION OF OHIO

CHAMFERING TOOL

Application filed November 4, 1929. Serial No. 404,533.

This invention relates to a tool adapted to be used for chamfering and other similar work on pistons or other cylindrical metallic members having one or more circumferential grooves or channels.

The general object of the invention is to provide a tool of the character stated, which may be easily set in position for working and which may be operated manually for performing the desired work, while it is guided by a circumferential channel in the member worked upon. In its adaptation for work on pistons, the tool is provided with comparatively thin bearing shoulders adapted to be inserted in one of the channels and to constitute a three-point bearing for supporting and guiding the tool while it is turned about the piston. A bit suitable for the nature of the work to be performed is secured in the tool in a plane adjacent to the channel in which the tool is guided. A number of shims are so arranged that as many of them as are needed may be adjusted on the faces of the shoulders to add to the thickness thereof, so that they will have a comparatively close fit in the channel.

The detailed construction of the invention in its preferred form will be more fully explained in connection with the accompanying drawings, in which:—

Figure 1 is a side elevation of the tool in operative position, the piston being shown partly in section.

Fig. 2 is a section taken on the line 2—2 of Fig. 1.

Fig. 3 is a section taken on the line 3—3 of Fig. 1.

According to the invention, the tool, which is shown in connection with a piston 5, comprises two shanks 6, pivotally connected at one end, as shown at 7, and normally extending adjacent each other to constitute a handle. The end portions of the shanks 6 remote from the pivot 7 are formed with oppositely disposed substantially arcuate jaws 8 and 9 terminating in bifurcated ears 10 and 11, respectively. A threaded spindle 12 is pivotally connected at 13 to the ear 10 and is provided with a nut 14, which may be screwed

against the ear 11 to draw the jaws toward the piston 5.

One of the jaws, as 8, is formed with an inwardly projecting shoulder 15 and the other jaw 9 is formed with two opposed shoulders 16 and 17. The tool is flattened in a plane transverse to the piston 5 and the shoulders 15, 16 and 17 are comparatively thin and adapted to enter one of the circumferential channels 18 of the piston and engage the bottom thereof so as to constitute a three-point bearing for the tool as the latter is turned about the piston. A number of shims 19 are mounted on the face of the jaw 8 by means of a screw 20 which engages an elongated slot 21, so that one or more of the shims may be advanced on the face of the shoulder 15 to increase the thickness of the latter to the width of the channel 18. Shims 22 are also mounted on the corresponding face of the jaw 9 and are formed with projecting portions 23 adapted to be similarly advanced along the faces of the shoulders 16 and 17 by means of the screws 24 and slots 25.

The tool, when it is thus set in one of the channels 11, is adapted to be turned about the piston to chamfer the edge of the channel. For this purpose a suitable bit 26 is mounted on one of the jaws, preferably on the side of the piston opposite to the shoulders 16 and 17. This bit is secured in a socket or chuck 27 by means of a set screw 28 and the socket is mounted in a slot 29 formed in the jaw 8. This slot is elongated in a radial direction so that the bit may be fed inwardly by means of a feed screw 30, which has a threaded connection with the socket 27. The jaw 8 is formed with a flange 31 in which the feed screw 30 is rotatably mounted and the latter is provided with a suitable head 32 by means of which it is rotated.

As illustrated in the drawings, the tool may be used for chamfering the lower edge of the lowermost channel 18, so as to provide space adjacent the piston ring to catch surplus oil and prevent the same from working into the firing chamber. By turning the tool over and mounting the same in the uppermost groove, with the position of the bit reversed, the tool may be used for chamfering the end 100

of the piston. By a suitable modification of the bit or in the manner in which it is mounted, the tool may be used for other similar operations on a piston or any other metallic member of similar shape. While I have shown and described in detail one form in which the invention may be embodied, it is to be understood that this is merely for the purpose of illustration and that the invention includes all such modifications as may fall within the scope of the appended claims.

What I claim is:

1. A tool comprising a handle consisting of two shanks pivotally connected at one end and formed at the other end with opposed jaws having inwardly projecting shoulders, means for adjusting the jaws so that said shoulders engage the circumferential channel of a piston to constitute a bearing for the tool, and means for mounting a bit in one of the jaws to engage the edge of the channel.
2. A tool comprising a handle consisting of two adjacent shanks pivotally connected at one end and formed at the other end with opposed jaws having comparatively thin inwardly projecting shoulders, means for adjusting the jaws so that said shoulders engage the circumferential channel of a piston to constitute a bearing for the tool, shims mounted on the faces of the jaws and individually adjustable into contiguous relation to the faces of said shoulders to add to the thickness thereof so that they may have a close fit in the channel, and means for mounting a bit in one of the jaws to engage the edge of the channel.
3. A tool comprising two jaws having comparatively thin opposed shoulders insertible in the circumferential channel of a piston so as to engage the bottom thereof and to constitute a bearing for the tool, shims mounted on the faces of the jaws and individually adjustable adjacent the faces of said shoulders to add to the thickness thereof so that they may have a close fit between the sides of the channel, a handle connected to said jaws, and means for mounting a bit in one of the jaws to engage the edge of the channel.
4. A tool comprising two opposed jaws, one having two comparatively thin inwardly projecting spaced shoulders and the other having a single similar shoulder, means for adjusting the jaws to bring said shoulders into close relation to the circumferential channel of a piston to constitute a three-point bearing for the tool, shims mounted on the faces of the jaws and individually adjustable adjacent the faces of said shoulders to add to the thickness thereof so that they may have a close fit between the sides of the channel, a handle connected to said jaws, and means for mounting a bit on the jaw having a single shoulder and in opposed relation to the other jaw.
5. A tool comprising two shanks arranged

normally adjacent each other to form a handle, said shanks being pivotally connected at one end and formed at the other end with opposed jaws having inwardly projecting shoulders, means for adjusting the jaws so that said shoulders engage the circumferential channel of a piston to constitute a bearing for the tool, a bit socket mounted for radial adjustment on one of the jaws, and a screw feed operatively connected with said socket.

6. A tool comprising two jaws having comparatively thin opposed shoulders adapted to be inserted in the circumferential channel of a piston and to engage the bottom thereof to constitute a bearing for the tool, means for adjusting said jaws toward or away from each other, a handle connected to said jaws, a bit socket mounted for radial adjustment on one of the jaws, and a screw feed operatively connected with said socket.

7. A tool comprising two opposed jaws, one having two comparatively thin inwardly projecting spaced shoulders and the other having a single similar shoulder, means for adjusting the jaws to bring said shoulders into close relation to the circumferential channel of a piston to constitute a three-point bearing for the tool, a handle connected to said jaws, a bit socket mounted for radial adjustment on the jaw having a single shoulder and in opposed relation to the other jaw, and a screw feed operatively connected with said socket.

8. A tool comprising a handle consisting of two normally adjacent shanks pivotally connected at one end and formed at the other end with opposed jaws having comparatively thin inwardly projecting shoulders, means for adjusting the jaws so that said shoulders engage the circumferential channel of a piston to constitute a bearing for the tool, shims mounted on the faces of the jaws and individually adjustable into position adjacent the faces of said shoulders to add to the thickness thereof so that they may have a close fit between the sides of the channel, a bit socket mounted for radial adjustment on one of the jaws, and a screw feed operatively connected to said socket.

9. A tool comprising two jaws having comparatively thin opposed shoulders adapted to be inserted in the circumferential channel of a piston and to engage the bottom thereof to constitute a bearing for the tool, shims mounted on the faces of the jaws and individually adjustable adjacent the faces of said shoulders to add to the thickness thereof so that they may fit closely between the sides of the channel, a bit socket mounted for radial adjustment on one of the jaws, and a screw feed operatively connected with said socket.

10. A tool comprising two opposed jaws, one having two comparatively thin inward-

ly projecting spaced shoulders and the other having a single similar shoulder, means for adjusting the jaws to bring said shoulders into contact with the bottom of a circumferential channel of a piston to constitute a three-point bearing for the tool, shims mounted on the faces of the jaws and individually adjustable adjacent the faces of said shoulders to add to the thickness thereof so that they may fit closely between the sides of channel, a bit socket radially adjustable on the jaw having a single shoulder and in opposed relation to the other jaw, and a screw feed operatively connected to said socket.

15 11. A tool comprising two shanks pivotally connected at one end and normally disposed adjacent each other to form a handle, a pair of substantially arcuate jaws connected with the handle at the end opposite the 20 pivotal connection and arranged to span a piston, said jaws being formed so as to engage a circumferential channel in the piston, ears on the free ends of said jaws, means cooperating with said ears to draw the jaws 25 toward each other into close relation to the channel, and means for mounting a bit on one of the jaws.

12. A tool comprising two shanks pivotally connected at one end and normally disposed adjacent each other to form a handle, a pair of substantially arcuate jaws connected with the handle at the end opposite the pivotal connection and arranged to span a piston, said jaws being formed so as to have a 30 three-point engagement with the bottom of a circumferential channel in the piston, shims cooperating with the bearing points and selectively adjustable to add to the thickness thereof so that they may have a close fit with 35 the sides of the channel, ears on the free ends of said jaws, means cooperating with said ears to draw the jaws toward each other into close relation to the channel, and means for mounting a bit on one of the jaws.

40 45 In testimony whereof I have hereunto signed my name to this specification.

ALBERT P. FALL.
